ELECTRIC SWITCH WITH LONGITUDINALLY SPACED TERMINALS AND A BODY OF CONDUCTIVE FLUID MOVABLE RELATIVE TO SAID TERMINALS

James L. Grupen, 1269 Lynn Way, Sunnyvale, Calif.
Filed July 1, 1964, Ser. No. 379,682
6 Claims. (Cl. 200—152)

This invention relates to an electric switch in which a body of conductive fluid is moved relative to two longitudinally spaced terminals and in which the fluid is maintained under pressure. The present application relates to a switch that is an improvement of the switch disclosed in Patent No. 3,142,739, issued July 28, 1964.

An object of this invention is to provide a switch, as above characterized, in which the fluid is formed with two ring portions that are in contact, one with each terminal, with a sleeve portion of the fluid connecting the ring portions when the switch is "on," and with one ring portion being separated from the other and from said sleeve portion of the fluid when the switch is "off."

This invention also has for its objects to provide such means that are positive in operation, convenient in use, easily installed in a working position and easily disconnected therefrom, economical of manufacture, relatively simple, and of general superiority and serviceability.

The above objects are realized in a switch structure that has an elongated insulating body, is provided with two longitudinally spaced switch terminals, an insulated operating stem moveable in a longitudinal bore in said body with a diametrically reduced portion of said stem forming, with the wall of the bore, an annular space in which a sleeve of conductive fluid is housed, the bore being enlarged where the same is in register with each terminal to provide rings of fluid larger diametrically than the sleeve of conductive fluid, and conductive means, using the terminals as abutments, to impose resilient pressure on said rings of fluid, both when the stem is positioned to have the sleeve of fluid between and connecting the rings of fluid and when the sleeve of fluid is displaced by the stem to separate one ring therefrom and from the other ring of fluid.

The invention also comprises novel details of construction and novel combinations and arrangements of parts, which will more fully appear in the course of the following description and which is based on the accompanying drawing. However, said drawing merely shows, and the following description merely describes, one embodiment of the present invention, which is given by way of illustration or example only.

In the drawing, like reference characters designate similar parts in several views.

FIG. 1 is a longitudinal view, partly in section and partly in elevation of the present switch in "on" position.

FIG. 2 is a similar view of said switch in "off" position.

FIG. 3 is a cross-sectional view as taken on the line 3—3 of FIG. 1.

The switch that is illustrated comprises, generally, an elongated dielectric body 5, an operating stem 6 of similar material longitudinally movable in said stem, cooperating means 7 formed in the body and stem to house a quantity of conductive fluid 8, longitudinally spaced terminals 9 and 10 extending preferably radially from said body, means 11, operatively associated with said terminals, for placing said conductive fluid under pressure, and boot means 12 to seal between the body 5 and stem 6 at the ends of the former.

The body and stem are advantageously formed of ceramic material, but may be made of other suitable dielectric material. The fluid may be any conductive fluid, such

2

as mercury or ionized gas. The boot means 12 is exemplary of sealing means at the indicated places primarily for excluding air-borne contaminants and dirt from the bearing faces of the switch parts 5 and 6.

5 The body 5 is provided with a longitudinal through bore 15, and the stem 6 with ends 16 that have a sliding fit in said bore. The stem is enough longer than the body so that said ends protrude beyond both ends of the body in all operative positions in the bore 15.

10 The cooperating means 7 comprises, in part, longitudinally spaced enlargements 17 in the bore 15, which, together with the portion 15' of bore 15, forms the shape of a dumbbell in the bore 15 and, in part, a diametrically reduced portion 18 connecting the stem ends 16. Said portion 18, as shown, has a length approximating the overall length of the enlargements 17 and portion 15'. As can be seen from FIG. 1, where the stem 6 is in centered position in the body 5, so that the stem portion 18 is co-extensive with the bore portions 15' and 17, the described 15 dumbbell shape is rendered hollow or sleeve-like. The conductive fluid 8 fills said hollow shape when the stem is thus centered.

20 Thus, the fluid 8, in that position of the stem 6, comprises two end rings of fluid 19 and a connecting sleeve of fluid 20 smaller in diameter than the rings 19.

25 The terminals 9 and 10 are shown as metallic members that extend radially from the body, each in register with one of the enlargements 17. Said terminals are shown with threaded ends 21 that extend from body portions 22 that are fixedly embedded or fitted into the body 5. The terminal ends may extend in the same direction, or in different relative directions, as shown.

30 The means 11 is shown as a piston element 23 in sliding sealing engagement with a radial bore 24 extending from each bore enlargement 17, the same being located in said radial bores inward of the body portions 22 of the terminals 9 and 10. A spring 25 in a seat formed in each body portion 22, is arranged to press against each piston element 23, thereby exerting a bias or pressure on the rings 19 of the fluid 8. Since said elements 23 exert their pressure on opposite ends of the fluid in the means 7, the entire body of such fluid is under the pressure of springs 25.

35 The boot means 12 are shown as flexible corrugated sleeves, one end sealed around the end of the body 5 and the other end sealed over the protruding end of stem 6 on the respective end of the switch.

Operation

40 With the stem 6 in a position, as in FIG. 1, with the reduced portion 18 thereof centered between the bore enlargements 17, the conductive fluid 8 that fills the enlargements 17 and the annular space defined between the bore portion 15' and said reduced portion 18 is maintained under pressure by the spring-biased piston elements 23. Consequently the terminals 9 and 10 are electrically connected and the switch is "on." With the stem 16 shifted endwise, as in FIG. 2, so that one end 16 thereof displaces part of the fluid 8 from connection with the fluid in one of the enlargements 17, thereby leaving a ring of fluid 19 in said enlargement, which is not in electrical engagement with the shifted part of the fluid, the terminals 9 and 10 become electrically separated. Therefore, the switch is "off." The bias of one piston element 23 is retained on the separated ring of fluid 19 and of the other piston element on the remainder of the fluid.

45 The above-described pressure on the fluid is present in all positions of the stem 6, at the "on" and "off" positions and all in between positions, as well. Hence the stem has a positive position which it tends to retain until moved therefrom by endwise force applied to either end of the stem.

The bore 15 may be blind at one end and the stem 6 project only from and be moved by its other end.

While the foregoing has illustrated and described what is now contemplated to be the best mode of carrying out the invention, the construction is, of course, subject to modification without departing from the spirit and scope of the invention. Therefore, it is not desired to restrict the invention to the particular form of construction illustrated and described, but to cover all modifications that may fall within the scope of the appended claims.

Having thus described this invention, what is claimed and desired to be secured by Letters Patent is:

1. An electric switch comprising:

- (a) an elongated dielectric body having a longitudinal bore with two longitudinally spaced bore enlargements located inward of the body ends, 15
- (b) an electric terminal extending from said body in register with each said bore enlargement,
- (c) an elongated dielectric stem in said bore having opposite ends in sliding engagement with the bore and provided with an intermediate portion of smaller 20 diametral size than the bore, the length of said smaller stem portion approximating the distance between the outer sides of the bore enlargements,
- (d) a quantity of conductive fluid filling the bore and its enlargements around the smaller portion of the stem when said stem has its small portion centered with respect to the bore enlargements, one of the ends of the stem separating a ring of fluid in one 25 bore enlargement from the remainder of the fluid when the stem and body are relatively shifted endwise, and
- (e) means to place pressure on the opposite ends of the quantity of fluid in the former position of the stem, and on the separated portions of the fluid in the latter 30 position of the stem.

2. An electric switch according to claim 1 in which the pressure-applying means comprises spring-biased elements between the inner ends of the terminals and the conductive fluid.

10
5

3. An electric switch according to claim 1 in which the pressure-applying means comprises spring-biased elements between the inner ends of the terminals and the conductive fluid, said elements comprising pistons.

4. An electric switch according to claim 1 in which the body bore is a through bore, the stem has its bore-fitting ends extending from the opposite ends of the body, and means is provided to seal both against leakage of fluid from the ends of the bore and to exclude air-borne contaminants from the bearing surfaces of the body and stem.

5. In an electric switch,

- (a) a dielectric body having an elongated bore with two longitudinally spaced bore enlargements located inward of the ends of the bore,
- (b) a quantity of conductive fluid in said bore,
- (c) means to place a continuously applied resilient bias on said quantity of fluid,
- (d) a stem longitudinally movable in the bore to more and longitudinally separate one portion of said body from another portion thereof to form separated quantities of fluid, and
- (e) a pair of longitudinally spaced electrical terminals in said body electrically connected by said fluid and electrically disconnected when one portion of said fluid is moved and separated from the other portion.

6. In an electric switch according to claim 5, the bore in the body having bore enlargements in register with the terminals, each separated portion of the fluid occupying one of said bore enlargements.
